US00D533357S

(12) **United States Design Patent** (10) **Patent No.:** **US D533,357 S**
Sarbo et al. (45) **Date of Patent:** **** Dec. 12, 2006**

(54) **SURFACE PATTERN FOR TOILET PAPER**

(75) Inventors: **Benjamin Charles Sarbo**, Winneconne, WI (US); **Dennis Patrick Rockhill**, Green Bay, WI (US)

(73) Assignee: **Kimberly-Clark Worldwide, Inc.**, Neenah, WI (US)

(**) Term: **14 Years**

(21) Appl. No.: **29/240,590**

(22) Filed: **Oct. 13, 2005**

(51) **LOC (8) Cl.** **05-06**

(52) **U.S. Cl.** **D5/26**

(58) **Field of Classification Search** **D5/1-3, D5/5, 7-8, 11, 13-16, 19-20, 23-28, 30, D5/32, 35-37, 39, 43, 45, 47, 49-50, 52-66, D5/99; D2/749, 994; D6/582-583, 595-596, D6/598, 608, 603-606, 613, 616, 617, 619, D6/622; 428/17-18, 151, 154, 156, 171, 428/187, 198, 199, 540, 542.2, 542.6, 919, 428/904.4; D24/124, 125, 126; D25/142, D25/152; 5/413 AM, 709; 162/134, 140, 162/109, 231; 156/148, 209; D7/396.4-5**
